UNITED STATES PATENT OFFICE.

HANS F. BAUER, OF CEDAR RAPIDS, IOWA.

VISCOSITY-TESTING APPARATUS.

1,190,085.

Specification of Letters Patent.

Patented July 4, 1916.

Application filed September 25, 1915. Serial No. 52,647.

To all whom it may concern:

Be it known that I, HANS F. BAUER, a citizen of the United States, residing at Cedar Rapids, in the county of Linn and State of Iowa, have invented new and useful Improvements in Viscosity-Testing Apparatus, of which the following is a specification.

My invention relates to a device or apparatus for determining the fluidity or viscosity of starches and modified starch, oils, gums, dextrins, varnishes and all liquids and solutions of the same general character.

The object of the invention is to provide an apparatus of the character set forth by means of which tests of the character defined may be easily, conveniently and accurately made.

The invention consists of the features of construction, combination and arrangement of parts herein fully described and claimed, reference being had to the accompanying drawing in which:—

Figure 1 is a side elevation of an apparatus of the character stated embodying my invention. Fig. 2 is a vertical section through the test tube or column and the flask. Fig. 3 is an enlarged detail view of a portion of the test tube.

In carrying my invention into practice, I provide a supporting upright 1 of any suitable type, which extends upward from a base 2, and which is provided with a desired number of adjustable arms or brackets 3 for supporting a vertically adjustable test tube 4. The upright 1 is also provided with an adjustable supporting ring 5 for a purpose hereinafter described. The tube 4 is of suitable length and diameter, and is provided at its lower end with a constricted discharge aperture 6, of a size to permit of the outflow of a predetermined quantity of fluid within a given time. This outlet communicates with a stop cock 7, which is employed as a cut-off and has a discharge passage of sufficient diameter to prevent interference with the free outflow of the liquid through the aperture 6.

The test tube and its parts are preferably made of glass, but may be made of any other suitable material, and said tube, as shown, is provided below its upper end with a level indicating mark 8 and at its upper end is provided with a vent top 9, which is adapted to be opened to permit of the discharge of air from the tube while the latter

is being filled; and of being subsequently closed to confine the column of liquid and form an air cushion to prevent fluctuations in the column, as hereinafter fully described.

Communicating with the tube 4 immediately below the indicating mark 8 is an inlet 10 connected with a filling cup 11 which is of a diameter to loosely receive the ordinary rubber tube 12 upon the neck portion 13 of an inverted flask 14 adapted to be held in the ring 5.

The apparatus may be employed for determining the fluidity or viscosity of any of the liquids or solutions mentioned, or other similar liquids or solutions, but for the purpose of explaining the operation of the apparatus its use in determining the viscosity of modified starch may be set forth as an example. As is well known, when starch is treated with a moderately strong alkali solution of sodium hydrate it thickens and assumes somewhat the consistency of thick starch paste. The sodium hydrate solution breaks up the starch cells similar to that of boiling the starch with water. Modified starches are known also as thin-boiling starches. Similar differences are noted in untreated starches, when boiled with water the untreated starches being thick boiling. The extent to which a starch has been altered or rendered thin-boiling is determined by treating a known amount of starch with a given amount of 1% of sodium hydrate solution, free from carbonate of soda and comparing its fluidity or viscosity with that of water at a temperature of 75° F. and noting how much will pass through a small aperture in a given time. The present apparatus is designed for determining the fluidity of starch or other liquid in this manner.

In practice, about twenty grams of the starch to be tested is dried at a temperature of about 200° F. Nine grams of the dried starch is then weighed out, placed in a beaker, and to this is added 20 cc. distilled water, a stirring rod being employed to break up all small particles of starch and to secure a thorough mixture. To the solution thus obtained is then added 180 cc. of 1% sodium hydrate solution at 75° F., the mixture being stirred gently for about three minutes and then poured into the flask 14, which may have a capacity of say 250 ccm. The solution is then allowed to stand exactly

thirty minutes and is placed in a water bath and maintained at a temperature of 75° F., while the test tube 4 is made wet with water and let drain. At the expiration of the time noted the flask 14 containing the starch solution is inverted and connected with the filling cup 11 by pinching shut the rubber tube 12 and inserting the flask into the ring 5 and the rubber tube into the cup 11, sufficient space being provided within the cup for the inflow of air to the flask to take the place of the solution discharging therefrom into the cup. The tube 12 is then relapsed so as to allow the cup 11 and tube 4 to fill up to the level of the indicating mark 8, the tube 4 having between such mark and the outlet 6 a containing capacity of 100 ccm. This filling of the tube and cup to the point indicated is obtained by closing the cock 7 and opening the cock 9 to permit the tube 4 to fill, after which the cock 9 is closed to seal the upper end of the tube, the cock 7 opened to allow any excess of solution above the mark 8 to discharge and then closed. The apparatus being thus set for operation, the cock 7 is opened to allow the solution to flow through the outlet 6 into a graduated receiver 15 supported upon the base below and in alinement with the tube, and which receiver may have the same measuring or containing capacity as the flask. The apparatus having previously been calibrated by introducing 250 cc. distilled water at 75° F. into the flask 14 and observing the time that it takes for 100 cc. of the water to run out, it is evident that the number of cc. starch solution running out in the same length of time will indicate the fluidity or viscosity of the starch. For instance, if 100 cc. of water at a temperature of 75° F. runs through the apparatus in thirty-five seconds, and 40 cc. of the starch solution at 75° F. runs through the apparatus in an equivalent amount of time, it is evident that the fluidity or viscosity of the starch is 40. The fluidity or viscosity is taken at a 10% moisture basis, nine grams of the dried starch used in the test being equal to a 10% moisture basis. It will be obvious from the foregoing description that my invention provides an apparatus by which the fluidity or viscosity of liquids of the stated character may be conveniently, quickly and accurately determined. The advantages of my improved apparatus, in addition to its simplicity, are, first, that the outflowing solution at the outlet 6 is always under a constant head or pressure,

secondly, that an accurate measurement of the liquid may be obtained by the use of the 60 cock 9 in bringing the solution to the level 8, before starting the test, third, when the cock 9 is closed, after bringing the solution to the point 8 an air cushion exists between the point and surface of the liquid at the point 65 8 which prevents any fluctuation of the solution in the column 4, and, fourth, by the inversion of the flask 9 into the cup 11 the supply of the solution is kept constant, ease of operation and accuracy thus being insured.

I claim:

1. An apparatus for testing the fluidity or viscosity of liquids comprising a test tube having a vent cock at its upper end, a valve 75 outlet at its lower end, a filling cup disposed parallel with and adjacent to the upper end of the tube, a lateral inlet connecting the tube with the lower end of said filling cup, and an indicating mark disposed above and 80 in proximity to said inlet connection.

2. An apparatus for determining the fluidity or viscosity of liquids, comprising a support, a test tube carried by the support, and having a vent cock at its upper end, a 85 valved outlet at its lower end, a lateral inlet adjacent to but below its upper end, a liquid level indicating mark disposed above and adjacent to said inlet, and a holder carried by the support to contain a vessel from 90 which the cup is to be filled.

3. An apparatus for determining the fluidity or viscosity of liquids comprising a test tube having a vent cock at its upper end, a valved outlet at its lower end, an inlet disposed adjacent to but below its upper end, 95 a liquid level indicating mark disposed above and adjacent to said inlet, and a filling cup communicating with the inlet.

4. An apparatus for determining the 100 fluidity or viscosity of liquids, comprising a support, a test tube carried by the support and having a vent cock at its upper end, a valved outlet at its lower end, a lateral inlet adjacent to but below its upper end, a liquid 105 level indicating mark disposed above and adjacent to said inlet, and a filling cup communicating with the inlet, and a flask carried by the support and having a neck portion depending into said filling cup.

In testimony whereof I affix my signature in presence of two witnesses.

HANS F. BAUER.
